A. L. WALLING.
WASHING MACHINE AGITATOR.
APPLICATION FILED MAR. 13, 1922.

1,428,822.

Patented Sept. 12, 1922.

UNITED STATES PATENT OFFICE.

ARCHIE L. WALLING, OF AKRON, OHIO.

WASHING-MACHINE AGITATOR.

Application filed March 13, 1922. Serial No. 543,301.

To all whom it may concern:

Be it known that I, ARCHIE L. WALLING, a citizen of the United States, residing at Akron, in the county of Summit and State 5 of Ohio, have invented certain new and useful Improvements in Washing-Machine Agitators, of which the following is a specification, reference being had to the accompanying drawings.

10 It is the purpose of the present invention to provide an agitator of this character, especially adapted for use in connection with any form of construction of clothes receiving receptacle, for instance in any ordinary 15 wash tub, whether of wood or metal, and furthermore it is the aim to employ the principle of suction, to agitate the clothes, and to force the suds back and forth through the clothes.

20 Still another purpose is to provide an agitator mounted for rocking movement in the receptacle or tub, in combination with a suitable handle carried by the agitator, for oscillating the same, in order to create a 25 suction action on the clothes.

A further purpose is the provision of an agitator, wherein a plurality of suction cups is used, preferably four in number, though it is obvious that any number of cups may 30 be employed, and disposed properly relatively to the bottom of the receptacle or tub and disposed on angles, in order to permit the agitator to oscillate.

In creating a suction on the clothes, the 35 dirt is readily removed from the soiled clothes as the agitator is rocked.

Additionally, the invention aims to provide an agitator, which may be easily disassembled, for shipment, and in view of the 40 parts, namely the suction cups, the supporting means therefor and the rocking shaft and handle are preferably connected; the various parts may be easily detached for repairs.

45 It is to be understood that the particulars herein given are in no way limitative and that while still keeping within the scope of the invention, any desired modifications of detail and desired proportions may be made 50 in the apparatus according to circumstances.

The invention comprises further features and combination of parts, as will be hereinafter set forth, shown in the drawings, and claimed.

In the drawings:—

55 Figure 1 is a plan view of the improved agitator arranged in applied position in a clothes receiving receptacle or tub;

Figure 2 is a vertical sectional view through the same on line 2—2 of Figure 1; 60

Figure 3 is a detail sectional view on line 3—3 of Figure 1; and

Figure 4 is a detail sectional view on line 4—4 of Figure 1.

Referring to the drawings, 1 designates 65 the clothes receiving receptacle or tub, which may be any construction and proportions, and constructed of any suitable material, preferably sheet metal, and is provided with a pair of oppositely disposed 70 handles, whereby the receptacle may be moved from one place to another.

A pair of hangers, oppositely disposed is mounted on the wall of the tub or receptacle. Each hanger 2 is constructed from a piece of 75 sheet metal bent to form an elongated portion to extend within the receptacle in engagement with its side wall, and to provide a short portion 3 overlying the wall of the receptacle upon the exterior thereof. A 80 thumb screw 4 is threaded in the portion 3 of each hanger, and its inner end has swivelled thereto a plate 5, bearing upon the exterior of the wall of the receptacle to bind or hold the hanger securely in position. 85

A rock shaft 6 is provided. This shaft comprises a plurality of sections, a central tubular section 7 and the two end sections 8, which are telescopically fitted into the opposite ends of the central tubular section 7. 90

Thumb screws 9 are carried by the tubular section 7, to hold the end sections 8 in different adjusted positions, enabling the rock shaft to be lengthened or shortened, to fit and accommodate itself to receptacles or 95 tubs of different diameters. The remote ends of the end sections 8 of the rock shaft have reduced journals 10, which are mounted in suitable bearings of the elongated portions of the hangers 2, for the purpose of supporting the rock shaft in position. As illustrated the elongated portions of the hangers 2 are provided with pluralities of apertures or bearings 11, it being the aim that the reduced journals are to engage in two opposite 100

bearings. By providing these pluralities of bearings or openings 11, it is possible to adjust the rockable shaft to different posi-

tions, with relation to the bottom of the receptacle or tub.

The agitator comprises a plurality of suction cups 12 and 13, which are arranged in 5 pairs. The suction cups 12 and 13 are disposed at an acute angle, so that the marginal lower edges of the walls of the cups will extend upwardly and outwardly, as shown in the transverse sectional view of 10 Figure 2, thereby enabling the agitator to oscillate freely, and yet insure a suction action on the clothes.

Depending from and secured adjustably to the sections 8 of the rock shaft are hangers 14. These hangers at their lower ends terminate in arms 15, which extend toward each other, and are disposed between the flanges of the suction cups 12 and 13. These arms 15 are V-shaped in cross section, and 20 are bolted at 16 to the flanges of the suction cups 12 and 13, in order to hold the cups at an acute angle. As previously stated the hangers 14 are adjustable on the rock shaft, and to hold them in different 25 positions suitable thumb screws 17 are threaded through their upper ends and designed to bear frictionally upon the shaft.

Suitable straps 18 are bolted at 19 to the upper wall of the suction cups, for the purpose of reinforcing the cups relatively to 30 each other, at right angles to their reinforcing connections previously set forth. These metal straps 18 are shaped to conform to the conical contour of the upper walls of 35 the suction cups, and secured to them by bolts 20 are the arms 21 of the angle pieces 22. The upstanding arms 23 of said angle pieces are secured by means of bolts 24 and wing nuts 25 to a suitable handle 26, which 40 extends upwardly, and is long enough to be grasped and oscillated manually.

In other words the journals of the sections 8 of the rock shaft are so mounted in their bearings of the hangers 2, as to permit the 45 shaft to freely rock, due to the oscillatory movement of the handle. The clothes are placed in the reception and the suds of a sufficient quantity to cover the clothes are also used. Obviously by moving the handle of 50 the agitator back and forth, imparting rocking movements to the shaft, and since the hangers 14 are made with the shaft and the angle pieces 22 fast to the straps 18, the suction cups 12 may be moved downwardly, 55 while the cups 13 elevate. When the cups 13 descend, the suction cups 12 ascend, that is due to the oscillatory movements of the

handle, hence the suction cups oscillate, one pair downwardly while the other upwardly and vice versa.

The invention having been set forth, what is claimed is:—

1. An agitator of the character indicated, a rocking shaft, hangers adjustably depending therefrom, a plurality of suction cups 65 carried by and connected to the hangers, said cups being arranged in pairs, said hangers having arms engaging between and secured to the flanges of said cups, said arms being substantially triangular in cross sec- 70 tion, whereby the suction cups may be supported at an acute angle, and means for rocking the shaft and oscillating the suction cups.

2. An agitator of the character indicated, 75 comprising a rocking shaft, hangers depending therefrom and provided with arms extending toward each other, a plurality of suction cups arranged in pairs, the construction and arrangement of said arms being such as to engage between the flanges 80 of the suction cups and hold the cups at an acute angle, thereby permitting the agitator to have a free rocking movement, and also enabling any pair of cups when brought 85 in contact with the clothes to assume approximately horizontal positions, whereas the other pair is tilted upward, for the purpose of breaking the suction, and vice versa, and means for rocking the shaft. 90

3. An agitator, comprising a rocking shaft including a handle, hangers depending from the shaft, a plurality of individually removable suction cups arranged and connected in pairs, supporting means detachably connected to all of the cups and suspended from the hangers, the construction and arrangement of said supporting means being such as to hold the cups at angles. 95

4. An agitator comprising a rocking shaft, 100 a plurality of individually removable suction cups, a handle having means connected to the cups and supporting them in pairs on opposite sides of the shaft, hangers depending from the shaft, supporting means suspended from the hangers and detachably connected to all of the cups, the construction and arrangement of said supporting means being such as to hold one pair of cups at an angle to the other pair of cups. 105

In testimony whereof I hereunto affix my signature.

ARCHIE L. WALLING.
